THOMAS WILSON AND JOHN W. APPLEYARD, OF CHICAGO,
ILLINOIS.

Letters Patent No. 89,107, dated April 20, 1869.

IMPROVED CARPET-STRETCHER.

The Schedule referred to in these Letters Patent and making part of the same

To all whom it may concern:

Be it known that we, THOMAS WILSON and JOHN W. APPLEYARD, both of the city of Chicago, in the county of Cook, and State of Illinois, have invented a new and useful Machine or Implement for Stretching and Putting Down Carpets, which we call a Carpet-Stretcher; and we do hereby declare that the following is a full, clear, and exact description of the construction and operation of the same, reference being had to the annexed drawings, making a part of this specification, in which—

Figure 1 is a perspective view.

Figure 2, a longitudinal elevation.

Figure 3, a plan.

Similar letters of reference indicate corresponding parts.

The following are the parts:

1. The board A.
2. Hooks, or claws c c c c c.
3. Pawl g, staple y.
4. Ratchet-wheels r r.
5. Windlass w.
6. Cord b.
7. Staple x.
8. Lever l.
9. Hook h, or awl and ring, or anything equivalent.
10. Slot s.
11. Posts p p.
12. Joints j j.
13. Pieces l l.

A is a peculiarly-shaped board, having numerous steel or iron claws c c c c c underneath, with slot s and staple x, and upon the upper side, at the termination of said slot, the windlass w, terminated at each end

with ratchet-pulleys, or wheels r r, supported by the posts p p, connected by the cord b to the hook h, operated by the lever l, in combination with the side-pieces l l and the pawl g, supported by the staple y.

When not in use, the cord b is wound upon the windlass w, and the hook h lies in the slot s. By crowding the lever l forward, the joints j j permit the free revolution of the windlass w, so as to unwind or wind the cord up as often as is desirable.

The machine is operated in the following manner, to wit:

It is put upon the carpet to be stretched to place at a convenient distance from the base-board to which the carpet is to be brought so that the claws c c c c c will take a firm hold of the carpet. The hook h being sharp-pointed, is drawn slightly into the floor, close to the base-board, and the cord b made of wire, or linen, or any other suitable material, is gradually wound upon the windlass w, by raising and falling the lever l, the pawl g operating to hold the same in its place as it turns the ratchet-wheels. The staple x serves to keep the tension and stretching in a right line from the carpet to the hook.

What we claim and desire to secure by Letters Patent, is—

The combination and arrangement of the board A, the claws c c, the pawl g, the ratchet-wheels r r, the windlass w, the lever l, the cord b, and the hook h, as and for the purpose specified.

THOS. WILSON.
JOHN W. APPLEYARD.
